UNITED STATES PATENT OFFICE.

HAROLD C. HATCHL, OF NACOGDOCHES, TEXAS.

AWNING-LOCK.

1,257,604.

Specification of Letters Patent. Patented Feb. 26, 1918.

Application filed November 3, 1916. Serial No. 129,376.

To all whom it may concern:

Be it known that I, HAROLD C. HATCHL, a citizen of the United States, residing at Nacogdoches, in the county of Nacogdoches 5 and State of Texas, have invented certain new and useful Improvements in Awning-Locks, of which the following is a specification.

The present invention has reference, generally, to improvements in curtains and awnings; and, the invention relates, more particularly, to a novel locking attachment therefor.

The invention has for its principal object 15 to provide a locking attachment for roll awnings or curtains and the like, whereby, the free end of the same when in unrolled or lowered position, will be engaged and retained in a fixed position and will not be 20 accessible from the outer side thereof, thereby, providing a device especially adapted for use upon sleeping porches and other similar places where it is desirable to provide means which will prevent intruders 25 from gaining entrance.

As an object of equal importance, the invention also aims to provide a locking device which can be readily attached to a porch or other construction, without materially altering 30 the same or detracting from the effect of the design thereof.

Among other aims and objects of the invention may be recited, the provision of an attachment of the character mentioned with 35 a view to compactness, and in which the number of parts are few, the construction simple.

Other and further improvements and novel details in the construction and arrangement of parts will be appreciated from 40 the description to follow, which, for a clear understanding of the invention should be considered in connection with the accompanying drawings forming a part hereof, 45 and wherein a preferred embodiment of the invention is shown for the purpose of illustration.

In the drawings:—

Figure 1 is a transverse section through a 50 supporting sill with the improved attachment applied thereon, the same being shown in side elevation;

Fig. 2 is a top plan thereof, and

Fig. 3 is a detail in perspective of one of 55 the supporting plates.

Similar characters of reference are em-

ployed in all of the above described views to indicate corresponding parts.

Referring now in detail to the several figures of the said drawings, I have shown by 60 way of illustration, the locking attachment as applied to a supporting sill 1, which sill may be used in conjunction with a sleeping porch or a window frame. However, in this connection it is to be noted that the device may be equally well adapted for use upon various constructions where it is desirable to provide an awning, shade or screen locking means. A plurality of horizontally aligned openings 2 are formed within the depending portions of the sill 1 and have arranged adjacent thereto guiding or supporting plates 3, the said plates being secured in position, by means of screws or other suitable fastening devices which are 70 passed through openings, generally indicated by the numeral 4 in the plates. Rectangular openings 5 are formed substantially centrally of the plates 3, in angularly disposed relation, the purpose of which will 75 be subsequently apparent.

Referring now to the locking means, whereby a stay bar 6 of the awning 7 will be retained in a fixed position, there is provided an arm 8, the said arm being twisted 85 intermediate its length, as at 9 and provided with a hooked portion 10. The forward portion of the arm is passed through the vertically arranged opening 5 in the plate 3, while the outer or rear portion thereof is 90 slidably engaged with the horizontally positioned opening in the remaining plate 3. A series of openings 11 are arranged within the forward part of the arm 8 and afford means whereby the locking element, which 95 will be presently described, can be adjustably engaged therewith.

With a view toward providing an efficient locking element, an arm 12 having a plurality of spaced apart openings 13 formed 100 therein, is employed. The forward end of the arm is bent or curved upon itself to provide a cam surface 14, which surface is adapted to be engaged with the adjacent face of the sill 1, when it is desired to move 105 the arm 8 into locked position. A bolt 15 is passed through certain of the openings formed in the arm 12 and also through one of the openings in the arm 8, whereupon a locking nut 15' is turned into engagement 110 therewith and the two elements thus, efficiently connected.

The operation of the attachment may be reviewed as follows:

The awning 7 when in unrolled or lowered position has the stay bar 6 thereof engaged by the hooked portion 10 of the arm 8, whereupon the outer end of the arm 12 is swung downwardly, causing the cam surface thereof to be engaged with the adjacent face of the sill 1, which action will 10 cause the lower portion of the awning to be drawn inwardly by the arm 8 and locked in a fixed position, when the said outer end of the arm 12 has been moved to its lowermost position, that is, when the cam surface as 15 afforded by the curved portion 14 is positively engaged with the sill 1. Obviously, by so locking the awning in position, withdrawal of the same, will be prevented and therefore, any attempts which might be 20 made to gain entrance at this point will be defeated.

While I have herein illustrated and described with a considerable degree of particularity, constructional details of the device embodying my invention, I do not wish to be understood as confining the invention to the particular form shown, nor to the exact construction, arrangement and adaptation of the parts shown and described, but I 30 reserve the right to make any changes and alterations that fairly fall within the spirit and scope of the invention.

What is claimed is:

1. In an awning lock, the combination of 35 a support, an arm projecting from said support, said arm terminating in a hooked portion, said hooked portion projecting toward said support, said hooked portion being adapted to receive the bar of an awning and 40 means for holding said arm in an adjusted set position.

2. In an awning lock, the combination of 45 a support, an arm slidably mounted upon said support, said arm having a hooked portion extending toward said support, said hooked portion being adapted to receive an awning bar, and a cam adjustably mounted upon said arm, said cam being adapted to engage said support for holding said arm 50 in an adjusted set position.

3. In an awning lock, the combination of a support, an arm slidably mounted thereon

and projecting thereon its outer surface, said arm terminating in a hooked portion extending toward said support, said arm 55 having openings formed adjacent its inner end, a second arm having a cam formed thereon, pivot means passing through said last mentioned arm and one of the openings in the first mentioned arm, whereby said last mentioned arm may be swung, thereby causing said cam to draw upon said first mentioned arm for moving said hooked portion toward said support, whereby an awning bar carried by said hooked portion may 60 be held in set position.

4. In an awning lock, the combination of an arm formed from a flat piece of material and twisted intermediate its ends, the outer end of said arm terminating in a hooked 70 portion, a flat arm pivotally mounted upon the other end of said first mentioned arm, a cam formed upon said last mentioned arm, whereby as said last mentioned arm is swung, said cam will cause said last mentioned arm to draw upon said first mentioned arm, thereby holding an awning bar, which may be carried by said hooked portion in set position.

5. In an awning lock, the combination of 80 a support having openings formed therethrough, plates fixedly mounted upon said openings and having rectangular openings formed therein, said openings extending at right angles to each other, an arm formed 85 from a flat strip of material twisted intermediate its ends and extending through said openings, whereby said plates will steady said arm, said arm having a hooked outer end, said hooked outer end being adapted 90 to receive an awning bar, an arm pivotally mounted upon the inner end of said first mentioned arm, said last mentioned arm having a cam formed thereon, whereby when said last mentioned arm is swung, it 95 will draw upon said first mentioned arm for retaining said hooked portion in an adjusted set position.

In testimony whereof I affix my signature in presence of two witnesses.

HAROLD C. HATCHL.
